UNITED STATES PATENT OFFICE.

GEORGE W. ROBERTS, OF WALLA WALLA, WASHINGTON TERRITORY.

GREEN-CORN-CUTTING MACHINE.

SPECIFICATION forming part of Letters Patent No. 296,066, dated April 1, 1884.

Application filed October 15, 1883. (No model.)

To all whom it may concern:

Be it known that I, GEORGE W. ROBERTS, of Walla Walla, county of Walla Walla, in the Territory of Washington, have invented an Improvement in Green-Corn-Cutting Machines; and I hereby declare the following to be a full, clear, and exact description thereof.

My invention relates to that class of machines designed to cut green corn from the cob or roasting-ear for canning and other purposes, and known as "green-corn-cutting machines;" and it consists in the combination of devices herein described and claimed, and all of which I shall hereinafter fully explain, reference being made to the accompanying drawings, in which—

Figure 1 is a perspective view of my machine. Fig. 2 is a bottom plan of the plate J and the knife K on an enlarged scale. Fig. 3 is a vertical section of same.

The object of my invention is to provide an effective machine for stripping corn from the cob for canning and domestic purposes.

A is a stand or frame having an upright supplementary frame, B, in which a cross-head or follower, C, is adapted to reciprocate. Depending from said cross-head are rods D, extending down through the table or stand, and connected with a vibrating treadle, E, under the table. Around the lower ends of these rods, between the treadle-frame and the base of frame B, are relief-springs F, which take the jar off the ascending movement of said treadle.

G G are counter-weights suspended by ropes H, passing over pulleys h h', and connected with the treadle, whereby said treadle, after being relieved of the downward pressure of the foot, may be raised again. In this manner the cross-head C is reciprocated, and in its downward movement is cushioned on springs I, set on frame A.

In the cross-head C is screwed a plate, J, in the center of which is a knife or cutter, K, having oppositely-extending arms L L, sliding on said plate. This knife is annular in shape, and is split into semi-circumferences,

the edges of which overlap, and are held together normally by means of the springs M, operating against lugs m on the arms L L. In this manner the knife or cutter is adapted to expand when brought down to encircle different sizes of roasting-ears.

In the center of stand A is a pin or spike, N, upon which the ear is to be impaled. This pin is directly under the knife, and has surrounding it an open space communicating with a drawer, O, in the table.

The operation of my machine is as follows: The ear, being of course previously stripped of its shucks, is impaled in an upright position on pin N. The treadle is then pressed down and the cross-head C descends; the knife encircles the cob and strips down the corn, which falls into the drawer O, from which, in due time, it may be removed. The weights then raise the cross-head for a repetition of the operation. The expanding property of the knife enables it to adjust itself to the various sizes of cobs.

I am aware that corn-cutting implements are known in which an expanding annular knife operates in conjunction with an impaling-pin in a vessel, and I do not therefore claim such device, broadly; but

What I do claim as new, and desire to secure by Letters Patent, is—

In a green-corn-cutting machine, the stand or table A, having spring-cushions I, supplementary frame B, central impaling-pin, N, and underlying drawer O, in combination with the cross-head C, having depending rods D, the pivoted treadle E, and cushion-springs F, the counter-weights G, and the expanding annular cutter or knife K on said cross-head, substantially as herein described.

In witness whereof I have hereunto set my hand.

GEORGE W. ROBERTS.

Witnesses:

J. D. LAMAN,
JOHN BRYANT.
